UNITED STATES PATENT OFFICE.

PETE M. MASOIAN, OF GRANITE CITY, ILLINOIS.

TRAVELING TEMPERATURE PLANT.

Application filed October 20, 1927. Serial No. 227,592.

This invention has for its object to provide a traveling temperature plant, the units of which consist of cars adapted to be coupled together in the form of a train and carrying apparatus adapted to control the temperature of those cars of the train which are used for transporting perishable commodities.

One unit of the plant includes a housing car body and refrigerating apparatus adapted to utilize any usual or suitable volatile liquid or substance such as ammonia, carbondioxide, etc. for the purpose of cooling, within the car, a refrigerating fluid such as brine and also adapted to circulate the brine through a refrigerator car coupled to the apparatus housing car, and to return the brine to the housing car for recooling, the organization being such that the operation of coupling a refrigerator car to the refrigerating plant car completes the brine circuiting system adapted to conduct cooled brine from the refrigerating apparatus to and through the refrigerator car and from the latter back to the former.

A further object of the invention is to provide as a unit of the train a refrigerator car having compartments at the opposite ends thereof with cooling coils housed therein and with means for determining the temperature of the compartments in the said car.

A further object of the invention is to provide as a unit of the train a car having a boiler mounted thereon and adapted to be used for supplying hot water to the circulating system when it is desired that the commodity be kept warm instead of being subjected to the preserving influence of a refrigerant. The idea of providing a separate unit having a heater is to avoid the necessity of taking the heat from the boiler of the locomotive which pulls the train, for the reason that locomotives need all of the energy and power that they are capable of generating to pull trains under prevailing conditions.

Railroad companies will not use a refrigerating system that takes its power from the locomotive and they will not permit the carrying or installation of a separate boiler upon the locomotive, for the reason that the locomotive is not at all times used for pulling trains, carrying fruit or perishable products and again the same fruit cars may be connected to another train of a different company. This would cause too much complication. In winter time, it would cause excessive weight to the load of the locomotive, because in the winter, cooling is not needed.

Refrigerator cars are usually filled with ice at the time that the perishable product is loaded or at the point from which the product is shipped. The refrigerating apparatus is intended to keep the ice from melting after the train has started on its journey. It will keep the ice in a solid condition, so that when the car reaches its destination, the original supply of ice is still in the car and should this car be disconnected from the train, it will be fully iced and will be able to stand on a side track for a long period of time before the ice melts. In the winter time, the same cooling coils that were used in summer may be used to keep the car at any uniform temperature that may be desired.

In the accompanying drawing:—

Figure 1 is a longitudinal sectional view of a refrigerating car and showing a fragment of the refrigerator car;

Figure 2 is a fragmentary plan view of piping used in the system;

Figure 3 is a side elevational view of a train of cars showing the refrigerator car in longitudinal section.

The refrigerator car consists of a body 1 having interiorly located partitions 2 spaced from its end walls and forming refrigerating compartments 3. Vertically disposed coils 4 are housed in the compartments 3 and an overhead pipe 5 connects the upper ends of the coils 4 together. The lower ends of the coils 4 are connected together by a lower pipe 6. The pipes 5 and 6 are disposed longitudinally of the body of the car. The pipe 6 has its end portions extended beyond the end walls of the body of the car and provided with valves 7 and coupling members 8.

The water heater consists of a boiler 9 mounted upon a car platform 10 and the said platform car is preferably coupled with the tender of the engine when the train is made up and is at the forward end of the train. The boiler 9 may be heated by oil or any other suitable fuel. A pipe 11 is disposed along the platform 10 and is connected with the boiler and is provided with suitable valves 11'.

The refrigerating apparatus carrying car 105 consists of a housing 12 having a compressor 13 mounted therein. The shaft 14 of the said compressor may be driven by any suitable motor operated by steam from the boiler or may be operated by an electric motor 17.

A condenser provided for liquefying the refrigerant may include a series of headers

19 which receive the refrigerant from the compressor. The headers are connected with receivers 21 and the receivers are connected with a cooler 22. The receivers are also connected with tanks 23. The compressor 13 is connected with an oil trap 24 and tanks 25. The said tanks are also connected with the headers 19. Hose coupling sections 26 are provided for connecting the tanks 25 with the pipe 11 upon the car platform 10 and a hose coupling section 27 is provided for connecting the cooler 22 with the pipe section 6 of the next adjacent refrigerator car. Said coupling sections are controlled by valves 28.

15 A hot water or steam pipe 29 is disposed along the housing 12 and may be connected with the pipe 11 upon the car platform 10 and the pipe 6 of the refrigerator car. The pipe 29 is used for leading hot water or steam from the boiler 9 to the coils 4 to warm the car body 1 when desired. The refrigerating plant which is carried in the housing 12 operates in a usual manner for supplying the refrigerant to the pipe 6 of the car body 1 when it is desired to keep the said car body cool. The compartments 3 are partly filled with water and when the refrigerant is passed through the coils 4, the said water is frozen into a solid mass. This will keep the car cool should it be disconnected and side-tracked for any length of time. The gauge 30 will indicate the temperature inside of the compartment. The temperature plant materially cuts down the cost of operating, for

the reason that only a few operators are necessary. It eliminates the hazard and danger of loss of life because it is not necessary for an operator to stay with the refrigerator cars while in transit. 35

Since the construction hereinbefore set forth is capable of a certain range of change and modification without materially departing from the spirit of the invention, I do not limit myself to such specific structure except as hereinafter claimed. 40 45

I claim:—

The combination in a travelling refrigerating plant, of a car, a refrigerating unit housed in said car and having a refrigerant line leading from the unit to the exterior, a coupling upon the outer end of said line, a refrigerator car adapted to be coupled to the first mentioned car, and having icing chambers at the ends thereof, a refrigerant conveying pipe extending longitudinally through the second mentioned car and exteriorly of the ends thereof and adapted to be coupled to the first mentioned refrigerant conducting pipe, and freezing coils in said compartments each connected at one end to the refrigerant carrying pipe passing through the chambered car and having a pipe line connecting their other ends together. 50 55 60

In testimony whereof I hereunto affix my signature. 65

PETE M. MASOIAN.
